UNITED STATES PATENT OFFICE

112,196

DESIGN FOR A VEHICLE BUMPER OR SIMILAR ARTICLE

Herbert S. Jandus, Detroit, Mich., assignor, by mesne assignments, to Hendaile-Hershey Corporation, Detroit, Mich., a corporation of Michigan

Application January 15, 1938, Serial No. 74,317

Term of patent 7 years

To all whom it may concern:

Be it known that I, Herbert S. Jandus, a citizen of the United States and a resident of the city of Detroit, in the county of Wayne and State of Michigan, have invented a new, original, and ornamental Design for a Vehicle Bumper or similar article, of which the following is a specification, reference being had to the accompanying drawing, forming a part thereof.

On the drawing:

The dominant features of my design are shown in solid black lines in the drawing.

I claim:

The ornamental design for a vehicle bumper or similar article, as shown and described.

HERBERT S. JANDUS.
